UNITED STATES PATENT OFFICE.

FLOYD J. METZGER, OF NEW YORK, N. Y., AND JOHN T. ORR, OF ELIZABETH, NEW JERSEY, ASSIGNEES TO AIR REDUCTION COMPANY, INCORPORATED, OF NEW YORK, N. Y., A CORPORATION OF NEW YORK.

CIRCUIT PROTECTIVE DEVICE.

Application filed November 1, 1922. Serial No. 598,305.

To all whom it may concern:

Be it known that we, FLOYD J. METZGER, a citizen of the United States, residing at New York city, in the county of New York, State of New York, and JOHN T. ORR, a citizen of the United States, residing at Elizabeth, in the county of Union, State of New Jersey, have invented certain new and useful Improvements in Circuit Protective Devices; and we do hereby declare the following to be a full, clear, and exact description of the invention, such as will enable others skilled in the art to which it appertains to make and use the same.

15 This invention relates to protective devices for electrical apparatus and circuits whereby stray currents at high potential may be excluded therefrom, the device being particularly adapted for use as a lightning 20 arrester although it is capable of diverting currents of much lower potential.

25 The device which is the subject matter of the present application may be utilized in connection with the various electrical circuits, particularly radio aerials, telephone and telegraph lines, railroad signal and other signal, lighting and power circuits.

30 The most common source of danger in electrical circuits is lightning, and it is usual to employ protective devices whereby currents from this source are diverted to the ground and thus prevented from damaging instruments and machinery or endangering persons who are working with such apparatus. The introduction of power transmission at high potentials has added another source of danger since the high potential conductors sometimes come in contact with circuits which are not designed to receive 35 currents of the character conveyed by power transmission lines.

40 The devices heretofore employed to divert currents at high potential have been of various kinds but depend generally upon the use 45 of a gap across which the high potential current may pass through air at varying pressures or through high resistance conductors such as granulated carbon. Such devices are not sensitive and have a low current capacity. They are useful, moreover, only in 50 diverting currents of very high potential such as lightning and provide no protection

against relatively low voltages such as are present in lighting and power lines.

The present invention depends upon the 55 use of gases of relatively high conductivity such as neon which, possessing a relatively low dielectric strength, is easily broken down to permit the passage of currents at 60 relatively low potentials and which, moreover, because of its conductivity, has a high current capacity, thus permitting the current from the source of high potential to pass 65 readily to the ground where it is dispersed. The use of neon for this purpose has been 70 suggested heretofore but protective devices containing neon have not been available, probably because of the fact that such devices are readily disrupted owing to the heating effect of the current in passing 75 therethrough. The electrodes employed in these devices have, moreover, been unsuited to the peculiar objects of the device, being of such a nature that they are readily destroyed by the current, particularly where 80 the area exposed to the gas is insufficient to permit the proper discharge of the current through the gaseous atmosphere. It has not been recognized, moreover, that the device should contain sufficient neon to provide 85 the desired capacity, and the failure to appreciate this and other limitations has resulted in the failure of all attempts to utilize neon for the purpose described.

It is the object of the present invention to 90 provide a device which overcomes the defects of high potential protectors as heretofore known and to provide a simple and effective means whereby high potential currents may be diverted from apparatus and 95 machinery of an electrical character, the device having an effective life which reduces the maintenance cost and ensures the desired protection.

In carrying out the invention the neon is 95 disposed within a tube, preferably of glass, having an external diameter of three-quarters of an inch or thereabouts and being approximately two inches long. The size 100 of the tube will vary with the desired capacity, the size stated being that best adapted for general purposes. The neon within the tube may be at any desired pressure, preferably between 5 and 50 mm., the pre-

ferred pressure being approximately 30 mm. of mercury. The tube is provided with electrodes spaced apart and sealed through the walls, the form of the electrodes being an 5 important feature of the present invention as is hereinafter more fully set forth.

We have discovered that in order to maintain the effective life of the tubes employed as protective devices, it is necessary to 10 distribute the heat which is generated by the passage of current therethrough. When a high potential current passes through such a tube for even a short period, the electrodes and the gas within the tube become 15 highly heated. Since the electrodes are of metal the heat is conducted rapidly to the walls of the tube where the electrodes are sealed therethrough, and the uneven heating of the glass results in shattering the 20 same, sometimes before the current has been fully diverted. This result, so far as it is caused by unequal expansion of the metal and the glass, may be avoided by the utilization of suitable metal for the electrodes 25 or lead-in conductors. Copper-clad conductors are preferred for this purpose. This precaution alone will not prevent shattering of the tubes. This may be avoided, however by providing two or more conductors leading to each electrode which are 30 sealed through the glass wall at points spaced from each other. The heat is by this means delivered to the glass in a more uniform manner and the tube thus protected 35 has a greatly increased life.

Another desirable feature of the present invention is the arrangement of the conductors in the form of loops which provide the desired electrode area. This structure 40 permits the provision of the electrodes in their simplest form, avoiding the joining of different metals or the use of electrodes of larger size than the conductors secured to the ends thereof. In all such constructions 45 it has been found that the electrodes become separated from the conductors at the first discharge of current through the tube and the tubes are thereafter worthless. The loops employed in accordance with the 50 invention may be variously arranged, being parallel to each other, for example, or disposed with their edges opposed. Preferably in a tube of the size described, a conductor having a diameter of .025 inch is 55 formed with the desired loops, and the ends are spaced apart and sealed through the wall of the tube. This provides a rigid support for the electrode in addition to its heat-distributing function, and tubes so constructed will permit the passage of currents of twenty amperes or more repeatedly 60 without destruction, a result which cannot be accomplished by tubes such as have been known heretofore.

In the accompanying drawing the preferred forms of the invention are shown by way of illustration, it being understood that these forms are merely suggestive and that the primary features of the invention may be utilized in various ways. 65

Fig. 1 is a side elevation of the invention; 70 Fig. 2 is a plan view thereof;

Fig. 3 is a plan view of an electrode of slightly modified form; and

Fig. 4 is an end elevation of one of the 75 electrodes shown in Fig. 3.

Referring to the drawing, 5 indicates a tube of glass or other suitable materials which may be of the dimensions hereinbefore stated or larger if the capacity of the tube is to be increased. It should be noted that a sufficient gas capacity is essential to the continued life of the tubes, and the capacity provided should be ample to convey the currents which may pass through 85 the tube. Two electrodes 6 are provided, the electrodes consisting of a looped conductor of suitable material as hereinbefore described. The ends of the coils are twisted at 7 to provide a rigid stem and the ends 8 are separated and sealed through the flattened ends of the tube. The ends 8 of the conductor distribute the heat from the electrodes and also serve as supports therefor so that the electrodes are quite rigidly held 90 in proper relation within the tube. 95

In Figs. 3 and 4 a slightly different form of electrode is illustrated, the only difference being in the arrangement of the loops 10 which are opposed in parallel relation. 100

The device described may be utilized in connection with electrical circuits in various ways. The conductors 8 at one end of the device should be connected to the ground in the usual manner of making ground connections and the conductors at the opposite end of the device should be connected to the circuit which is to be protected. In the case of wireless installation the device 110 is in a shunt connected to the aerial and to the ground. The device may be in a similar manner connected to telegraph, telephone, railroad signal and other circuits. 115

The large capacity and the stability of the 120 construction described ensures an extended life for the device. Current may pass repeatedly between the electrodes without endangering the glass tube or destroying the electrodes. The necessity of constantly replacing the device is thus avoided and the avoidance of constant inspection which would otherwise be necessary in the maintenance of a circuit protected by safety devices is a considerable advantage, particularly where thousands of such devices are installed as in railroad signaling work. 125

While the invention has been described

with particular reference to tubes containing neon, it is to be understood that the device embodying the electrodes may contain gases other than neon. Thus the atmosphere of the device may be of rarefied air or of helium, argon, nitrogen, hydrogen, etc., or mixtures thereof.

Various changes may be made in the details of construction and arrangement of 10 the parts without departing from the invention or sacrificing any of the advantages thereof.

We claim:—

1. In a safety device for electrical circuits the combination of a frangible vessel and electrodes therein consisting of loops adapted to provide a relatively large surface area, each electrode having two branched conductors sealed through the 20 wall of the vessel in spaced relation, the conductors being twisted within the vessel to provide a stiff support for the electrodes.
2. An electrode comprising a looped con-

ductor twisted adjacent the loop to provide a stiff support therefor. 25

3. An electrode comprising a looped conductor twisted adjacent the loop to provide a stiff support therefor and having two or more branches adapted to be sealed through the wall of a receptacle. 30

4. In a safety device for electrical circuits the combination of a vessel and electrodes therein, each consisting of a plurality of turns of wire forming a coil, the wire being twisted behind the coils to provide a 35 stiff support therefor.

5. In a safety device for electrical circuits, the combination of a vessel and electrodes therein, each consisting of a plurality of turns of wire forming a coil, the coils being disposed edge to edge with their axes in parallel relation. 40

In testimony whereof we affix our signatures.

FLOYD J. METZGER.
